UNITED STATES PATENT OFFICE.

CHARLES BOOZ, OF BUFFALO, NEW YORK, ASSIGNOR TO HENRY M. BIRGE,
OF SAME PLACE.

DESIGN FOR WALL-PAPER.

SPECIFICATION forming part of Design No. 26,088, dated September 22, 1896.

Application filed August 5, 1896. Serial No. 601,823. Term of patent 3½ years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

10 The design consists of ornamental figures arranged at regular distances apart with a series of ribbons interlacing with said figures and forming diamond-shaped panels, as represented in the accompanying drawing.

15 The border of said design is also formed of

similar ornamental figures with ornamental scrolls diverging right and left and connected by upright interlacing ornaments, as shown in the drawing.

What I claim is—

- 20 1. The design for wall-paper herein shown and described.
2. In the design for wall-paper the border herein shown and described.

Witness my hand this 1st day of August, 25
1896.

CHARLES BOOZ.
